CLAIM

The ornamental design for a portable refrigerator, warmer, or the like, as shown and described.

DESCRIPTION

FIG. 1 is a perspective view of a portable refrigerator, warmer or the like, showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a perspective view thereof, with the door shown open, in an upright position.

*Fig. 1.**Fig. 2.**Fig. 3.**Fig. 4.**Fig. 5.*

*Fig. 6.**Fig. 7.*
